LOOP CUTTING MACHINE

Leland F. Remington, Worcester, Mass., assignor
to Curtis & Marble Machine Company, Worcester, Mass., a corporation of Massachusetts

Application July 26, 1940, Serial No. 347,718

13 Claims. (Cl. 26—12)

This invention relates to machines for cutting warp loops or floats at the back of woven fabrics. Such loops appear, for instance, in fancy fabrics having spots or dots at spaced intervals on the face. Between the spots the special warp threads which form the spots are floated at the back of the fabric. The usual finishing shear will not trim warp-wise loops or floats until the loops are first severed, so that the free ends can be drawn up by suction for engagement by the shear cutters. It is accordingly found necessary to run such fabrics through a loop cutting machine before they can be sheared and finished.

It is the general object of my invention to provide a loop cutting machine of an improved construction and capable of operating at a substantially increased speed. A further object is to provide a machine in which reciprocating cutting parts are avoided, with corresponding absence of vibration at high speed.

In the preferred construction, I provide a plurality of rotating cutters each operative to cut the loops on a relatively narrow lengthwise strip of the fabric but collectively covering the full width of the fabric. I also make special provision for presenting the warp loops to the respective cutters and for holding the cut end of one loop as the next successive loop is being cut.

My invention further relates to arrangements and combinations of parts which will be herein-after described and more particularly pointed out in the appended claims.

A preferred form of the invention is shown in the drawings, in which

Fig. 1 is a side elevation of my improved loop-cutting machine;

Fig. 2 is a partial front view, looking in the direction of the arrow 2 in Fig. 1;

Fig. 3 is a partial plan view, looking in the direction of the arrow 3 in Fig. 2;

Fig. 4 is a plan view, looking in the direction of the arrow 4 in Fig. 1 and showing the arrangement and distribution of the rotating loop cutters;

Fig. 5 is a diagrammatic side elevation, showing the path of cloth travel in my improved machine;

Fig. 6 is a partial front elevation of certain parts, taken along the line 6—6 in Fig. 5;

Fig. 7 is an enlarged front elevation of a cutter head;

Fig. 8 is a detail sectional view, taken along the line 8—8 in Fig. 7;

Fig. 9 is a partial plan view of a cutter blade support;

Fig. 10 is a partial plan view showing the cutter operation; and

Fig. 11 is a diagrammatic view showing the overlapping arrangement of the raised strips across the width of the fabric.

My improved loop cutting machine comprises side frame members 10 (Fig. 1) spaced apart by the usual connecting girders (not shown) and provided with a series of forwardly projecting brackets 11 on which are mounted transversely extending channel bars 12 which support a plurality of cutter motors M and cutter-heads H, H' and H².

Each motor M is connected by a belt 14 (Fig. 4) to drive one of the cutter heads H, and each head H is connected by a belt 15 to drive a second cutter head H'. In certain cases, the head H' is connected by a third belt 16 to drive an additional cutter head H². The motors and cutters at the right of the center line of the machine rotate clockwise, while those at the left rotate anti-clockwise, so that the cutting action is always toward the nearer selvage.

The belts and pulleys are of the V type and the pulleys 20 (Fig. 1) on the motors M are each formed in two parts which may be moved axially toward or away from each other, so that the effective diameter of the pulley may be varied, with a corresponding variation in the speed of the rotating cutter blades driven thereby. A bolt and slot connection is provided between each motor M and its channel bar 12, so that the motor can be adjusted transversely of the machine to take up slack in the belt, when the effective diameter of a pulley 20 is changed.

The detail construction of the cutter heads is best shown in Figs. 7, 8 and 9. Each cutter head comprises an upright shaft 22 (Fig. 8) rotatable in upper and lower ball bearings 23 and 24 mounted in a fixed housing 25, which is bolted to the channel-bar 12. Pulleys 27 and 28 are secured to the upper end of the shaft 22 in each cutter head H, and one or more pulleys corresponding to the pulley 28 are provided on the upper shafts in the heads H' and H². A cutter blade support 30 is threaded on the lower end of the shaft 22 and is held from relative rotation by a set-screw 31, which seats itself in a longitudinal groove 32 in the shaft 22. The shaft 22 is provided with collars 34 and 35 (Fig. 8) which locate the shaft 22 vertically and prevent vertical displacement.

Close vertical adjustment of the cutter blades is secured by turning the cutter blade support 30 on the threaded lower end of its shaft 22, and by

retaining the angular adjustment by seating one of the screws 31 in one of the longitudinal grooves 32. As there are three equally spaced screws 31 and two oppositely disposed grooves 32, there is a locking position of the cutter head every 60°, so that close vertical adjustment may be secured and retained.

Each cutter blade support is provided with three radial arms 37 having enlarged outer ends 38 each provided with a threaded stud 39 and with a pair of dowel pins 40. Each arm 37 is provided with a cutter blade 42 having an attaching portion 43 provided with openings for the stud 39 and dowel-pins 40. A wing nut 44 is threaded on each stud 39 and secures the cutter 42 in position.

Each cutter blade 42 (Figs. 7 and 9) has a laterally extending cutting portion provided with a beveled upper cutting edge 45 and with a rounded loop-engaging end 46. Each cutter blade is curved in a horizontal plane, as shown in Fig. 9, and is inwardly eccentric to a circular arc, for a purpose to be described.

The motors M and connected cutter heads H, H' and H² are arranged in a series of banks as shown in Fig. 1, and each bank is provided with a pair of guide-rolls 50 and 51 (Figs. 1 and 5). Each bank except the lowermost is also provided with an additional front guide-roll 52. Spaced sleeves 53 are provided on each guide-roll 50 or 51, and these sleeves are held in adjusted position by setscrews 54 seating in longitudinal grooves 55 in the guide-rolls. A nip roll 60 is provided to coact with the sleeves 53 on each rear guide roll 51. The nip rolls 60 are mounted on swinging arms 62 (Fig. 1) and rest freely on the cloth passing over the rear guide-rolls 51.

The machine is also provided with a lower guide-roll 64 (Fig. 1) for the cloth C, and with a tension or drag roll 65 having an adjustable friction clamp 66, a guide-roll 67, a spreader roll 68, a guide-roll 69, a spreader roll 70 and guide-rolls 71 and 72. The cloth C then passes over a driven drum 75 (Fig. 1), under a guide-roll 76, over an upper guide-roll 77, and past guide-rolls 78 and 79 and a spreader roll 80 to a drum 81 above which a cloth roll R is formed by any usual winding mechanism not shown in detail and which forms no part of the present invention.

The winding drums 75 and 81 are belt-driven from a motor M' through a variable speed mechanism 90 controlled by a hand wheel 91.

The electrical connections of the machine include a main switch S (Fig. 1) by which the cloth feed motor M' and all of the cutter head motors M may be simultaneously started or stopped. A switch S' is also provided by which the motors M may be held inoperative while the motor M' only responds to the switch S. This is of advantage in threading the machine.

I also provide a reversing switch S² (Fig. 4) for the motors M in each bank of cutter heads. If the motors M are in operation and any one of the switches S² is manually reversed against spring pressure, the motors M in the associated bank will be promptly reversed and will rotate in the reverse direction so long as the switch is held against the spring pressure, which tends to restore it to normal forward position.

The wiring connections from the power lines to the several switches and motors are of ordinary arrangement and are not shown herein, as they form no novel feature of the present invention.

Having described the details of construction of my improved machine, I will now explain the method of operation.

Assuming that the cloth C has been threaded 5 through the machine and is being drawn upward by the winding drum 75, the cloth is first tensioned by the tension or drag roll 65, is then spread to full width by the spreader roll 68, and is drawn over the guide-rolls 50 and 51 associated with the lowest bank of cutter heads. Each coacting pair of sleeves 53 (Fig. 10) on these rolls is aligned with the axis of the cutter head with which they are associated. These sleeves preferably have tapered end portions, as indicated 10 at 53^a, so that the cloth will be drawn more smoothly thereover. The inner beveled end of each sleeve 530 (Fig. 6) which is adjacent the cloth selvage is preferably knurled, as indicated at 53^b, to provide a limited spreading effect.

As the cloth C is drawn over a coacting pair 15 of sleeves 53, a narrow longitudinal strip of the cloth will be raised or displaced above the normal plane of the cloth, as indicated at C' in Figs. 6 and 10. The cutter blades 42 are adjusted vertically so that they just clear these raised strips 20 of cloth and so that their rounded ends 46 will engage and pass under the floating warp threads W which form the loops. This action is indicated in Fig. 10, in which a loop is about to be severed by a cutter blade 42.

At this same time, the severed ends of the last 25 previously cut loop are held by the nip roll 60, so that these severed ends will not be pulled out of the fabric when the cutter blade 42 engages 30 the next loop.

It will be noted that the cutter blades of each 35 head engage the loops only in a narrow longitudinal strip centered on the axis of the cutter shaft and extending a relatively short distance to each side thereof. Consequently the cutter blades move approximately perpendicular to the loops during the cutting operation. It will also be noted that the strip of cloth is not positively supported at the locus of action of the loop-engaging head 46 but is stretched between two 40 guide-rolls. Consequently the cloth can yield slightly when thus engaged and cutting or tearing of the cloth is avoided.

As the cloth C is being drawn in the direction 45 of the arrow a in Fig. 10 during the cutting operation, it will be evident that if the cutter blade were formed in a true circular arc, the loop threads would be dragged crosswise of the cutting edge of the blade while cutting was taking place. 50 As the entering end of the cutter blade is inwardly eccentric, however, the cutting point on the blade moves rearwardly with the cloth as the cutter blade advances through the loop. With a suitable speed relation between the angular movement of the cutter blade and the rearward movement of the cloth, the blade may be caused to complete the cut substantially at the point of initial contact with the loop and with complete avoidance of the dragging action above described, which would rapidly dull any cutting edge disposed in a true circular arc.

The cutter heads are so arranged that the various longitudinal strips C' overlap as shown in Fig. 11, so that the cutters collectively operate 55 over the entire width of the fabric.

The additional front guide-rolls 52 (Fig. 5) are provided so that the cloth may not approach the guide-rolls 50 at an abrupt angle. No guide-roll 52 is provided for the lowest bank, however, 60 as the spreader roll 68 serves the same purpose.

The strips C' are more easily raised when the angle of approach is relatively slight.

The manual control of the machine is extremely simple. If the switch S' is open and the switch S is closed, the feed motor M' may be operated to draw the cloth along for threading operations, without rotating the cutter heads. If the switch S' is closed, the feed motor M' and cutter head motors M will all be simultaneously controlled by the switch S.

When in the operation of the machine a transverse seam between two pieces of cloth approaches, the reversing switches S² (Fig. 4) may be pushed successively to reverse rotation of each bank of cutter heads as the seam passes thereunder. By having a separate switch for each bank, the loop-cutting operations of each bank of cutters need be suspended only as the seam passes thereunder, whereas simultaneous reversal of all of the cutter head motors would necessarily keep all the cutters inoperative until the seam had passed all four banks, during which period a considerable length of cloth would have passed uncut.

The rate of cloth feed is controlled by the hand wheel 91. It is obvious that the cloth may be fed more rapidly with relatively long floats than with short floats, as less loop-cutting operations per yard are required. The speed of rotation of the cutters in each bank of cutting heads may also be adjusted by varying the effective size of the driving pulleys 20, as previously described.

As the cloth passes upward from the guide-roll 16 to the guide-roll 11, it is preferably drawn over the black surface of an inspection-board 109, so that any uncut loop may be easily detected.

It has been the previous custom in loop-cutting machines to use reciprocating knives which cannot be operated at high speed without excessive vibration. The practical working limit of such machines has been not over six or eight yards per minute, whereas my improved machine, which avoids the vibration of reciprocating parts, may be operated at speeds several times greater. Speeds of from thirty to forty yards per minute are found entirely practical.

Having thus described my invention and the advantages thereof, I do not wish to be limited to the details herein disclosed, otherwise than as set forth in the claims, but what I claim is:

1. In a loop cutting machine, means to temporarily raise transversely separated longitudinal portions of the cloth above the general plane of the cloth, and means to sever the warpwise loops in each longitudinal raised portion with the cutting portion of each severing means moving substantially transversely to the longitudinal path of travel of the cloth during the severing of each loop.

2. A loop cutting machine comprising means to feed and guide a piece of cloth therethrough, means to raise narrow longitudinal strips of said cloth above the general plane of the cloth, and a separate rotating loop cutter for each longitudinal strip, adjacent longitudinal strips being positioned to overlap edgewise, and said strips collectively including the whole widthwise extent of the cloth.

3. A loop cutting machine comprising means to feed and guide a piece of cloth therethrough, a plurality of loop cutters mounted to rotate about separate axes substantially perpendicular to the plane of the cloth at the cutting locus and mounted in a series in which the loop-cutting

fields of action overlap transversely of the cloth, and means to rotate said cutters so that the cutting action of each cutter is toward the nearer selvage.

4. A loop cutting machine comprising means to feed and guide a piece of cloth therethrough, guide-rolls disposed in pairs over which the cloth is drawn, said guide-rolls having portions of greater diameter coacting with the cloth to raise longitudinal strips thereof above the plane of the cloth, a cutter head for each raised strip, and cutter blades on each cutter head rotated above and closely adjacent one of said raised strips and effective to sever warpwise loops thereon.

5. The combination in a loop cutting machine as set forth in claim 4, in which each blade is formed in an inwardly eccentric curve in its plane of rotation and with its loop-engaging end rotating at the shortest radius.

6. A loop cutting machine comprising means to feed and guide a piece of cloth therethrough, guide-rolls disposed in pairs over which the cloth is drawn, said guide-rolls having portions of greater diameter coacting with the cloth to raise longitudinal strips thereof above the plane of the cloth, a cutter head for each raised strip, and cutter blades on each cutter head rotated substantially parallel to the plane of said raised strips and closely adjacent one of said strips, said blades having upper cutting edges and rounded loop-engaging ends and being effective to pick up and sever warp-wise loops on said raised strips.

7. A loop cutting machine comprising means to feed and guide a piece of cloth therethrough, a plurality of loop cutting units mounted above said cloth and each rotated about a separate axis substantially perpendicular to the plane of the cloth at the cutting locus, motors for said cutters mounted at the sides of the machine and beyond the selvages of the cloth, and driving connections through which each motor rotates a plurality of said cutting units.

8. In a loop cutting machine, a plurality of rotated loop-cutting heads spaced apart transversely of the cloth and mounted in a plurality of banks spaced longitudinally of the cloth, means to feed and guide a piece of cloth under said heads and in planes substantially parallel to the planes of rotation of the cutters, motors to drive said cutters, and a separate manually-controlled means for each bank, effective to simultaneously reverse all of the motors and cutters in said bank as a seam passes thereunder.

9. In a loop cutting machine, a plurality of rotated loop-cutting heads spaced apart transversely of the cloth and mounted in a plurality of banks spaced longitudinally of the cloth, and means to feed and guide a piece of cloth under said heads and in planes substantially parallel to the planes of rotation of the cutters, certain of said cutters rotating clockwise and certain of said cutters rotating anti-clockwise and each cutter rotating in such a direction that the loop-cutting action thereof is toward the nearer selvage.

10. A loop cutting machine comprising means to feed and guide a piece of cloth therethrough, and a plurality of loop-cutting heads mounted in separate banks, the heads in each bank being spaced apart transversely of the cloth and each head being out of longitudinal alignment with every other head, and said heads collectively coacting with the entire width of the cloth.

11. A loop cutting machine comprising means to feed and guide a piece of cloth therethrough,

a plurality of loop-cutting heads mounted in separate banks, with the heads in each bank spaced apart transversely of the cloth and with each head out of longitudinal alignment with every other head, said heads collectively coacting with the entire width of the cloth, and means to present a separate longitudinal raised portion of the cloth to each cutter head.

12. In a loop cutting machine, a plurality of rotated loop-cutting heads spaced apart transversely of the cloth and mounted in a plurality of banks spaced longitudinally of the cloth, and means to feed and guide a piece of cloth under said heads and in successive planes substantially parallel to the planes of rotation of the cutters.

13. In a loop cutting machine, means to draw

a piece of cloth longitudinally through said machine at a predetermined rate of cloth travel, a loop-cutting blade rotating about a fixed axis substantially perpendicular to the plane of the cloth at the cutting point, said blade performing a cutting action in a direction substantially transverse to said longitudinal travel and having an elongated cutting edge radially positioned at a progressively varying distance from its axis of rotation, and means to rotate said cutting blade at a speed so correlated to the predetermined rate of cloth travel that the point on a loop engaged by a cutting blade will not be substantially shifted longitudinally of the cloth or loop during the loop-cutting operation of said blade thereon.

LELAND F. REMINGTON.
